DRIVE FOR ROTATING BRUSHES, WHEELS, ETC

Filed Dec. 20, 1926

INVENTOR:

Otis R. Hasty

By Frederick P. Parker
Attorney

UNITED STATES PATENT OFFICE

OTIS R. HASTY, OF ELGIN, ILLINOIS, ASSIGNOR TO HASTY-JOHNSON CORPORATION,
OF ELGIN, ILLINOIS, A CORPORATION OF ILLINOIS

DRIVE FOR ROTATING BRUSHES, WHEELS, ETC.

Application filed December 20, 1926. Serial No. 156,055.

My invention relates to rotating brushes, buffing wheels, polishing wheels, grinding wheels, etc., and to means for holding and driving such brushes and wheels.

The principal objects of my invention are, to provide improved means for permitting one brush or wheel of the character herein set forth to be removed from a rotating holder or driving shaft, and another such brush or wheel to be substituted therefor, without stopping the rotation of the said holder or driving shaft; to provide manually-operable means for releasing the drive on a brush or wheel of the character herein set forth, and such brush or wheel itself, while the whole is rotating, to permit the said brush or wheel to be removed from its holder or driving shaft without rotating, while the said holder or driving shaft continues to rotate; to provide an improved holder and improved driving mechanism for brushes and wheels of the characters herein set forth; to provide an improved portable holder or driving shaft for brushes and wheels of the characters herein set forth, and an improved handle portion for such portable holder or shaft; to provide improved flexible driving mechanism for the aforesaid portable holder or driving shaft; and to provide other improvements in apparatus of the character herein set forth. Other objects will be apparent from the following disclosure of the invention.

On the accompanying sheet of drawings, illustrating one form of my invention, Figure 1 is a longitudinal sectional view of one form of portable rotating-brush or rotating-wheel holder of this invention, with portions shown in elevation, the said holder carrying a removable brush or wheel of the character herein set forth which is also shown in cross-section; Fig. 2 is a sectional-elevational view of a portion of a flexible shaft connected to a motor armature, and a portion of a flexible casing for the flexible shaft playably con-

nected to the motor frame; Fig. 3 is a cross-sectional view of the device shown in Fig. 1, with the rotatable brush or wheel removed, taken on plane 3-3 of Fig. 1; Fig. 4 is an elevational view of one of the hub end-plates 50 on the rotatable brush or wheel structure of Fig. 1; Fig. 5 is a cross-sectional view of the rotatable driving shaft of the device of Fig. 1, taken on plane 5-5 of Fig. 1, with a portion shown in elevation; Fig. 6 is a side-elevational view of the spring-controlled trigger carried by the rotatable driving shaft of the device of Fig. 1, showing the relation of the said trigger to the said rotatable shaft; and Fig. 7 is a cross-sectional view of the 55 rotatable driving shaft of the device of Fig. 1, taken on plane 7-7 of Fig. 1. Like characters refer to like parts in the several figures of the drawings.

In the use of ordinary rotating brushes, buffing wheels, polishing wheels, grinding wheels, etc., it is necessary to stop the rotation of the driving shaft carrying such brush or wheel when it is desired to substitute one brush or wheel for another, and to manipulate a nut to permit such substitution to be made. Stopping the rotation of the driving shaft of course necessitates bringing the said shaft up to the proper speed again after the desired substitution of the proper brush or wheel is made. This stopping and starting of the driving shaft, together with manipulating the said nut, consumes considerable time, especially where one brush or wheel is substituted for another quite frequently, as, for instance, in shining or polishing shoes, and in doing various other buffing and polishing jobs.

In my present invention I have devised a device wherein one brush or wheel of the character herein set forth may be quickly and easily substituted for another such brush or wheel on a driving shaft without stopping the rotation of the driving shaft or having to manipulate a nut. Such a device entirely

overcomes the disadvantages above mentioned and consequently saves considerable time that heretofore was wasted. The convenience and advantages of such an improved device are therefore thought to be very apparent.

I will now describe my invention more in detail by reference to the embodiment thereof disclosed in the accompanying drawings.

Referring to the drawings, 1 is a flexible shaft and 2 is a flexible casing therefor. One end of the flexible shaft 1 is connected to the armature of an electric motor 3, preferably as shown, so that when the said armature rotates it rotatably drives the flexible shaft 1. The member 4 is soldered or rigidly attached to the motor end of the flexible casing 2, and is loosely connected to the frame of the motor 3 by bolts 5, 5, preferably as shown, so as to hold the flexible casing 2 against rotation but permit it to have end play relatively to the flexible shaft 1. The end play of the flexible casing 2 permits the flexible shaft 1 and casing 2 to be more easily bent to various positions during the use of the flexible shaft 1. 6 is a hollow handle portion which is securely attached to the end of the flexible casing 2 away from the motor 3 by means of a portion 7 which is soldered or rigidly attached to the flexible casing 2 and screwed to the portion 6, preferably as shown. 8 is a driving shaft which is rotably mounted inside of the handle portion 6 in suitable bearings 9, 10. The shaft 8 projects from the free end of the handle portion 6 preferably as shown, and is held against any appreciable end movement by means of the bearing 9 and the portion 7 co-operating with an enlarged end portion 11 thereof. The end of the flexible shaft 1 away from the motor 3 terminates in a pin 12 which is rigidly secured to the shaft 1 preferably by solder and has a flat side 13. The pin 12 is rotatably located inside of the handle portion 6, and projects into the driving shaft 8, preferably as shown. The shaft 8 is provided with a flat side 14 toward the inner end thereof, which co-operates with the flat side 13 of the pin 12, as shown in Figs. 1 and 3, whereby the flexible shaft 1, when rotated, causes the driving shaft 8 to rotate therewith. It will be understood that the flexible shaft 1 and the flexible casing 2 of Fig. 1 are continuations of the flexible shaft 1 and the flexible casing 2, respectively, of Fig. 2. 15 is a rotatable brush, buffing wheel, polishing wheel, grinding wheel, or other wheel, having a hollow hub portion 16 adapted to slip over the protruding end 17 of the driving shaft 8. The hub portion 16 is provided with transverse annular recesses 18, 18 in the inner surface thereof at the respective ends thereof. The hub portion 16 also carries end plates 19, 19, each plate 19 being provided with inwardly-projecting portions 20, 20 which extend into the corresponding annular recess 18.

21 is a trigger which is pivotally mounted at 22 in a slot 23 in the driving shaft 8. 24 is a coil spring which acts on the trigger 21 so as to cause a portion 25 of the trigger 21 to normally project out from the side of the driving shaft 8. When the brush or wheel 15 is placed onto the protruding end 17 of the driving shaft 8, to the position shown in Fig. 1, with either end of the hub structure 16 placed toward the handle portion 6, the end plate 19 which is nearer the handle portion 6 first depresses the projecting portion 25 of the trigger 21 to a position within the confines of the driving shaft 8, which permits the said end plate 19 to pass over the portion 25 of the trigger 21, after which the spring 24 causes the portion 25 of the trigger 21 to again project out from the side of the driving shaft 8, this time into the annular recess 18 in the end of the hub structure 16 nearer the handle portion 6, as shown in Fig. 1, whereby the brush or wheel 15 is securely retained on the driving shaft 8 and locked thereon. Now when the driving shaft 8 is rotated, in either direction, the projecting portion 25 of the trigger 21 laterally engages one of the portions 20, 20 of the hub structure of the brush or wheel 15, in the annular recess 18 into which the portion 25 of the trigger 21 projects, and thereby drives the brush or wheel 15 with the driving shaft 8. The two end plates 19, 19, at opposite ends of the hub structure 16, permit the brush or wheel 15 to be reversed, or turned end-for-end, on the driving shaft 8, thereby, in effect, reversing the drive on the brush or wheel 15. 26 is a spring-controlled manually-depressible member which extends into the outer end 17 of the driving shaft 8 and at the same time projects from the end 17 of the shaft 8. The coil spring 27 tends to force the member 26 out of the end 17 of the shaft 8, but the pin 28 limits the outward movement of the member 26. The outer end of the member 26 is provided with a convenient cap 29 adapted to slide farther into the hollow end 17 of the shaft 8 when depressed. The cap 29 is preferably loosely attached to the member 26, so that when depressed while the member 26 is rotating, the pressure thereon will hold it from rotating and thus prevent it from rubbing on the member 26 pressed thereagainst. When the member 26 is depressed farther into the shaft 8, preferably by pressing on the cap 29 with the palm of the hand, or in any other suitable manner, either while the shaft 8 is rotating or while it is stationary, the inner end of the member 26 co-operates with the trigger 21, as thought to be well understood from the drawings, and moves the trigger 21 from the position 30 to the position 31, Fig. 6, in which latter position the portion 25 of the trigger is brought to a position within the confines of the driving shaft 8. Bringing the projecting portion 25 of the trigger 21 from 130

the position shown in Fig. 1 to the position shown in Fig. 6, relatively to the driving shaft 8, releases the drive on the brush or wheel 15 and simultaneously unlocks the brush or wheel holder, thereby permitting the brush or wheel 15 to be stopped, when rotating, and removed from the protruding end 17 of the driving shaft 8 without rotating, while the driving shaft 8 continues to rotate. This permits one brush or wheel 15 to be substituted for another such brush or wheel on the driving shaft 8 without stopping the rotation of the latter. Of course such a substitution may also be made while the driving shaft 8 is at rest. The advantages derived from such a device are thought to be now well understood.

I do not wish to limit this invention to the particular details herein set forth, as many modifications thereof may be made or utilized without departing from the scope of the appended claims. Neither do I desire to limit this invention to certain uses, as the uses to which it may be put are numerous.

25 What I claim herein as my invention is:

1. A flexible shaft, means for driving the flexible shaft, a hollow handle portion, a secondary shaft rotatably mounted inside of the said handle portion and projecting from the end of the latter, means for casting the flexible shaft, when rotated, to drive the said secondary shaft, a wheel of the character set forth having a hollow recessed hub structure adapted to slip over the protruding end 30 of the said secondary shaft, mechanism carried by the said secondary shaft and co-operating with the said recessed hub structure when the said wheel is placed onto the said secondary shaft whereby the said wheel 35 is retained on the said secondary shaft and is driven therewith when the latter is rotated, and spring-controlled manually-depressible mechanism extending into the outer end of the said secondary shaft and co-operating 40 with the first said mechanism when depressed, for causing the first said mechanism to release the drive on the said wheel and simultaneously unlock the wheel retainer, while the said secondary shaft is rotating, 45 to permit the said wheel to be removed from the said secondary shaft without rotating, while the flexible shaft and the said secondary shaft continue to rotate.

2. A shaft, means for driving the said shaft, a wheel of the character set forth having a hollow recessed hub structure adapted to slip over an end of the said shaft, mechanism carried by the said shaft and co-operating with the said recessed hub structure when the said wheel is placed onto the said shaft whereby the said wheel is retained on the said shaft and is driven therewith when the latter is rotated, and spring-controlled manually-depressible mechanism extending into the said end of the said shaft and co-operat-

ing with the first said mechanism when depressed, for causing the first said mechanism to release the drive on the said wheel and simultaneously unlock the wheel retainer, while the said shaft is rotating, to permit the said wheel to be removed from the said shaft, without rotating, while the said shaft continues to rotate.

As inventor of the foregoing I hereunto subscribe my name, this 13th day of December, 1926.
